VAMP FOR A SHOE

Albert R. Lakow, New York, N. Y.

Application December 15, 1953, Serial No. 28,082

Term of patent 3½ years

(Cl. D7—7)

To all whom it may concern:

Be it known that I, Albert R. Lakow, a citizen of the United States of America, residing in New York city, county of New York, and State of New York, have invented a new, original, and ornamental Design for a Vamp for a Shoe, of which the following is a specification, reference being had to the accompanying drawing, forming part thereof.

Fig. 1 is a plan view of a vamp for a shoe, showing my new design.

Fig. 2 is an edge view thereof.

Fig. 3 is an enlarged fragmentary plan view of the vamp for a shoe as shown in Fig. 1.

I claim:

The ornamental design for a vamp for a shoe, substantially as shown.
